UNITED STATES PATENT OFFICE.

EDWARD D. SCHMITT, OF BROOKLYN, NEW YORK, ASSIGNOR TO MONARCH SEAL COMPANY,
OF NEW YORK, N. Y., A CORPORATION OF NEW YORK.

MACHINE FOR APPLYING BOTTLE-SEALS.

No. 880,406.

Specification of Letters Patent.

Patented Feb. 25, 1908.

Application filed May 11, 1907. Serial No. 373,076.

To all whom it may concern:

Be it known that I, EDWARD D. SCHMITT, a citizen of the United States, residing at Brooklyn, in the county of Kings and State 5 of New York, have invented certain new and useful Improvements in Machines for Applying Bottle-Seals, of which the following is a specification.

This invention relates to machines for applying bottle caps and particularly to a 10 means for applying and locking hard metal caps to a bottle or like vessel, having an annular locking shoulder or surface adjacent to its mouth, into engagement with which the 15 flange of the cap is forced.

The invention relates more particularly to the construction of the sealing head, which it will appear to those skilled in the art, may be employed in machines of this character, regardless of any special means for 20 lowering the head or raising the bottle seat, it being immaterial to my invention which of the parts is moved; so long as there is a movement of one of the parts or both of the parts 25 to get the desired and required sealing pressure. I have shown the head mounted on a frame of ordinary construction in which the head is depressed toward the bottle seat, and returned to normal position by a spring or 30 springs, but as this invention does not reside in the machine or in the means for raising and lowering the head, these parts will not be described in detail, save in so far as it is 35 desirable to show a means for moving the head.

In the drawings: Figure 1 is a side elevation of the machine; Fig. 2 is a central section of the head with a bottle cap in dotted lines in the seal holding cavity of the plunger; 40 Fig. 3 is a similar view the parts of the mechanism of the head being in about the position they occupy or assume at the moment the flange of the cap is locked into holding engagement with the locking surface or 45 shoulder of the bottle, the upper portion of a bottle with a cap thereon being shown in section; Fig. 4 is a horizontal section of the plunger taken about on line *a*—*a*, Fig. 2; Fig. 5 is a cross section taken about on line *b*—*b* Fig. 50 2, showing the spring-backed pins for temporarily holding the bottle cap in the plunger preparatory to the sealing operation.

Referring to the drawings, the numeral 1 designates the machine frame, having a 55 broadened base 2 and a tubular column 3,

through which passes a vertically movable rod 4, attached to a web 5 integral with the head 6. Suitably connected with the rod is a treadle 7 by which the rod and head are moved together vertically, the head being 60 positioned and guided over a suitable bottle seat 8. The treadle and head are returned to normal position by a suitable spring 9, as is usual in machines of this character. The casing 10 is formed with a lower cylindrical 65 portion 11 and a reduced upper portion 12, the lower portion being provided with a bore 13, and the upper portion with a reduced bore 14.

The plunger is designated by the numeral 70 15. It is made with a number of radial recesses 16 cut in from its periphery in which are arranged pivoted seal locking levers 17, preferably six in number. These levers are each provided with short inwardly extending indenting points 18, which are simultaneously projected into the seal holding cavity 18' of the plunger to pinch the flange of the cap at intervals under the shoulder on the bottle, when the sealing pressure has been 80 applied and the seal seated. Intersecting these recesses 16 are a corresponding number of radially arranged apertures 19, that pass from the periphery of the plunger to the central opening 20 therein. The upper arms 85 of the seal locking levers extend into the recesses 19, where their inner faces are engaged by springs 21, whose inner ends are seated in cups 22, formed with rounding or cam surfaces 23, which are engaged by the bevel or 90 cam surface 24 of a rod 25. This rod is held fast at its upper end within a screw cap 26, and has no vertical movement in the operation of the head parts, although as will appear later, the rod may be adjusted vertically to 95 vary the point at which its bevel will engage the cups 22. The connection between the rod and cap is a threaded one, whereby said rod may be adjusted up or down to vary the point at which the cam surface 24 thereon 100 will engage the rounded ends or cam surfaces 23 of the caps 22. The adjustment is maintained by means of a lock nut 27, provided with spanner holes 28 by which it may be conveniently turned on the threaded portion 105 29 of the rod. Interposed between the nut 27 and the upper edge of a reduced extension 30 of the plunger is the sealing spring 31, which normally holds the plunger seated upon the ledge 32 of a ring 33, which ring is 110

connected to the casing by threads 34 and obviously readily removable when it is desired to have access to the plunger parts, the construction serving to facilitate the ready 5 assembling or separation of the parts.

The numeral 35 designates a series of spring-backed pins, that work in recesses 36, the springs serving to project the ends slightly into the seal cavity 18' to hold the seal preparatory to applying it to a bottle.

Modifications in the described construction may be made within the spirit of this invention, and while I have described the sealing head as especially adapted for applying 15 hard metal flanged caps to bottles having an annular locking surface or shoulder adjacent to their mouths, it will be understood that the heads would be equally adapted for applying caps or covers to vessels other than 20 bottles, such as glass jars, cans, etc., it being obviously only necessary to vary the dimensions of the head part to accommodate them to such additional uses.

Claims.

- 25 1. In a machine for applying bottle seals, a sealing head non-rotatable on its own axis a yielding seal applying plunger in said head and having a plurality of recesses therein, a seal locking lever rockably mounted in each 30 recess, a stationary cam element, slideable devices carried by the plunger adapted to engage the stationary cam element for the purpose set forth, and a yielding means interposed between said slideable devices and the 35 seal locking levers above their pivotal points, whereby upon the upward movement of the plunger the levers will be rocked to lock the seal.

2. In a machine for applying bottle seals, a sealing head non-rotatable on its own axis, a 40 yielding seal applying plunger in said head and having a plurality of recesses therein, a seal locking lever rockably mounted in each recess, slideable devices carried by the plunger and provided at their inner ends with 45 cam surfaces, yielding means interposed between said devices and the rockable seal locking levers, an adjustable cam element for operating the slideable devices, whereby the point at which in the movement of the 50 plunger, a seal may be locked, is varied.

3. In a machine for applying bottle seals, a sealing head non-rotatable on its own axis, a yielding seal applying plunger in said head, 55 said plunger having a seal holding cavity therein, and means for temporarily holding the seal in said cavity, said plunger being also provided with recesses, seal locking levers pivotally mounted in said recesses and formed with indenting points at their lower ends, a stationary cam element, slideable devices mounted in the plunger and having cam surfaces adapted 60 to engage the cam element, yielding means interposed between said slideable devices in the upper ends of the seal locking levers, 65 through which, when said devices engage the cam element, the lower ends of the locking levers are rocked into the seal cavity to indent the flange of the seal into locking engagement with the bottle.

In testimony whereof I affix my signature in presence of two witnesses.

EDWARD D. SCHMITT.
